N. HATCH.

UNION SUIT.

APPLICATION FILED, MAY 17, 1916.

1,213,482.

Patented Jan. 23, 1917.

Nathan Hatch, INVENTOR

Conrad C. Billings, BY
his ATTORNEY

UNITED STATES PATENT OFFICE.

NATHAN HATCH, OF ALBANY, NEW YORK.

UNION-SUIT.

1,213,482.

Specification of Letters Patent. Patented Jan. 23, 1917.

Continuation in part of application Serial No. 92,595, filed April 31, 1916. This application filed May 17, 1916. Serial No. 98,010.

To all whom it may concern:

Be it known that I, NATHAN HATCH, a citizen of the United States, and a resident of Albany, county of Albany, and State of New York, have invented certain new and useful Improvements in Union-Suits; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

25 The invention relates to an article of wearing apparel more particularly to union under garments for men, women and children.

One of the objects of the invention is to construct a union suit to fit the body of the wearer perfectly and securely and to make it very easy to put on and take off.

Another object is to so construct the garment that it will be self-supporting over the shoulders of the wearer by overlapping flaps, at least one of the shoulder flaps being free so that a maximum opening at the top of the garment will be provided in order to slip the garment on and off of the body 26 of the wearer.

Other objects will appear from the following description and claims.

The garment is so constructed that it may be very easily doffed and as easily slipped off the body of the wearer, yet while being worn it is securely and effectually held in place upon the body due to the new and particular construction of the shoulder and neck portions. Furthermore, the construction of 40 the garment is such that the neck portion when opened will extend entirely to the outer portion of the shoulder on each side so that the neck opening will be of sufficient size to pull up around any portion of 45 the body.

The garment is put on the body of the wearer by inserting the legs through the open neck portion into the leg portions, in the usual way, and then the upper portion 50 of the garment is drawn up around the upper portion of the body, the arms are inserted into the sleeves and the neck portion will then close over the shoulders, the free shoulder flap being secured to the front portion of the garment by button and button-

hole or any other suitable securing means as will be hereinafter more specifically described.

This application is filed as a continuation in part of my application Serial No. 92,595, filed April 21st, 1916.

Referring to the drawings; Figure 1 is a front view of the union suit embodying my invention. Fig. 2 is a front view of the upper portion of a union suit, the lower part being broken away, one shoulder flap on one side thereof being free and turned back to illustrate the construction. Fig. 3 is a front view of the pattern blank of the upper or body portion of the garment (the securing button being shown in place) before securing the sleeves and the shoulder flaps in place, one sleeve being shown in dotted lines upon the figure, one of the front shoulder flaps being turned forward at the other side of the figure. Fig. 4 is a side view of Fig. 2 with the sleeve removed, looking in the direction of the arrow.

In the detailed description, similar reference characters indicate the same parts in the several views.

The part marked A represents the body portion of the garment, B the leg portions and C the arm portions. Extending from the points 2 and 3 at or about the arm pits, are front and back flaps E and F covering the chest and back of the body respectively. The back flap is bounded by the lines 2, 4, 6, 8 and 3, and the front flap is bounded by the lines 2, 5, 7, 9 and 3. The lines 2, 4, 2, 5, 3, 6, 8, and 3, 9, form the arm holes. The upper portions of the front and back flaps are cut away in a substantially curved line so as to make a nicely formed neck opening and at the same time provide shoulder flaps which are to be turned over the shoulder, the shoulder flaps extending from the chest flap E being secured at their outer edges to the sleeves, and the shoulder flaps extending from the back flap F being secured at one side of the garment at their outer edges to the sleeve, the outer edge of one of these shoulder flaps being free from the points 20, 21 and secured only between the points 26, 22, thereby forming a free shoulder flap H which is secured at 24 to another securing means 24 upon the front of the garment.

While I have provided a button and button-hole for this securing means, it is of

course obvious that any other suitable securing means may be utilized.

Referring to Fig. 4, the shoulder flaps formed at the upper and outer corners of the front or chest flap are turned over the shoulder so that they will be underneath the upper and outer corners of the shoulder flaps of the back flap as clearly shown in Figs. 1, 2, 3 and 4. The outer edges of the shoulder flaps are secured throughout their length to the sleeve on one side of the garment. On the other side of the garment, the outer edge of the upper shoulder flap is left free from a point directly on top of the shoulder as at 20 in Fig. 4, and may come near the center of the shoulder as shown in Fig. 2 or be substantially parallel with the front sleeve seam as shown in Fig. 1.

I preferably turn the back shoulder flaps over the front shoulder flaps so that the suspenders of the wearer will not tend to cause a buckling of either flap, which might be the case should the front shoulder flap be turned over the back shoulder flap.

25 The outer side edges of the shoulder flaps are either secured by sewing or other suitable means to the sleeve and to each other throughout their length on one side of the garment.

30 Preferably on one side of the garment, the top shoulder flap formed from the back flap F is left free between the points 20 and 21 and the free end of this flap is secured to the front of the garment by button-hole and 35 button as indicated at 23 and 24, or by any other suitable means.

If desired, the top shoulder flap may be left free as indicated in Fig. 4, on both sides of the garment, and suitable means provided 40 to temporarily secure the free ends of the flaps to the body of the garment.

With my improved construction, when the union suit is adjusted in place upon the body of the wearer, the upper shoulder flaps will 45 rest and bind down upon the lower shoulder flaps, thereby holding the garment secure in place upon the shoulders of the wearer without danger of any portion of the garment becoming misplaced. At the same time, 50 these flaps can be pushed aside by the hands leaving a full opening at the upper portion of the garment amply sufficient in order to permit the wearer to disrobe.

The simplicity of construction and the 55 cheapness at which this garment can be made, as well as the great comfort afforded the wearer, renders this garment of great utility.

It is of course within the scope of my invention to arrange the free flap and place 60 the securing means upon either side of the

garment, that is either on the right or left, as may be convenient to the wearer.

The garment may be made of either woven, knitted or other suitable fabric, and 65 except for the novel features of construction which form my invention, it is made in the usual way; namely the leg portion may be long or short, the arm portions long or short; the leg and arm ends are ribbed and 70 finished as usual and the border of the neck and shoulder flaps are finished in the usual manner.

The garment may also be provided with an open and overlapping fly construction 75 and it is provided with the usual substantially longitudinal opening in the seat thereof.

I have illustrated and described the embodiment of my invention which I believe 80 to be the one best accomplishing the object which I have in view; nevertheless the invention is not restricted in details except as definitely expressed in the claims.

Having now described my invention, what 85 I claim as new and desire to secure by Letters Patent, is:

1. A union suit provided with chest and back flaps, the upper corners of said flaps being formed into shoulder portions, the 90 pair of shoulder portions formed from the chest flap extending rearwardly of the horizontal medial line of the shoulder, and the pair of shoulder portions formed from the back flap extending forwardly of said horizontal line of the shoulder, the upper edges of the chest and back flaps being free to form both the body and neck openings, one of the shoulder flaps being free.

2. A union suit provided with chest and 100 back flaps extending from points substantially at the arm pits, the upper corners of said flaps being formed into shoulder portions, the pair of shoulder portions formed from the chest flap extending rearwardly of 105 the horizontal medial line of the shoulder, and the pair of shoulder portions formed from the back flap extending forwardly of said horizontal line of the shoulder, the upper edges of the chest and back flaps being 110 free to form both the body and neck openings, one of the shoulder flaps being free, and means for detachably securing its end to the body of the garment.

In witness whereof I have hereunto set 115 my hand, at borough of Manhattan, city of New York, county of New York, and State of New York, this 11th day of May, 1916.

NATHAN HATCH.

In presence of—

GEO. H. SUTTON, Jr.,
ISABEL R. RICHARDS.
